FIG. 5 is a rear elevational view; and

FIG. 6 is a bottom plan view.

The characteristic feature of my new design resides in
the appearance of the bottom of the shoe sole wherein
the length of the forwardmost crest is more than half
again as much as the length of the two equal length rear
crests, the apices of all three crests being generally in
the same plane all as shown best by FIGS. 1 and 4.
